HEADREST FOR MEDICAL PRACTICE
CHAIRSNorman E. Lauterbach, Newark, N. Y., assignor
to Ritter Company, Inc., Rochester, N. Y., a
corporation of DelawareOriginal application July 2, 1946, Serial No.
680,983. Divided and this application October
1, 1949, Serial No. 119,096

4 Claims. (Cl. 155—177)

1

This invention relates to head rests for chairs of the variety adapted for use by the medical profession during examinations, treatments and minor operations, one object of the invention being to provide an improved head rest having a more adaptable, convenient and efficient construction.

Another object is to provide a chair of the above character having head, back, arm, and foot rests adjustable to and from positions lying substantially in the plane of the chair seat, for converting the chair into a substantially flat, table-like support.

Another object is the provision of a chair having a head rest adapted to be selectively positioned to afford either the usual head pads, or substantially flat rigid surfaces for supporting the head and neck of a patient against sagging during administrations of an anaesthetic. A further and more specific object is to provide a head rest having means for automatically locking the flat head supporting surfaces in position for use.

This application is a division of my copending application Serial No. 680,983, filed July 2, 1946, now Patent No. 2,558,143, granted June 26, 1951, Medical Practice Chair, to which reference may be had for parts disclosed but not claimed herein.

To these and other ends the invention resides in certain improvements and combinations of parts, all as will be hereinafter more fully described, the novel features being pointed out in the claims at the end of the specification.

In the drawings:

Fig. 1 is a side elevation of a chair embodying the present invention and arranged to support a patient in upright sitting position;

Fig. 2 is a side elevation of the same with parts of the seat broken away and arranged to support a patient in a substantially horizontal position;

Fig. 3 is an enlarged side elevation of the head rest detached, with its flat surfaces in one head supporting position;

Fig. 4 is a rear view of the same with its flat surfaces in the above supporting position;

Fig. 5 is a top plan view of the head rest with its flat surfaces locked in supporting position;

Fig. 6 is a similar view with the head pads in supporting position;

Fig. 7 is an enlarged sectional elevation substantially on the line 20—20 in Fig. 6, and

Fig. 8 is a sectional plan view substantially on the line 21—21 in Fig. 7.

The present invention is shown as applied to a medical practice chair having a seat 49 (Fig. 1),

2

to the back of which is pivoted at 50 a post 51. Slidably adjustable on post 51 is a back rest frame 52 having its upper end pivotally connected with the rear end of arm rest frames 53. These frames have their forward ends pivoted to the sides of the seat frame 49 and control the sliding of the back rest frame 52 as it is tilted rearwardly toward a horizontal position under control of counterbalancing springs on the seat frame and locking means operated by lever 54. The rear side of frame 52 carries an adjustable slide 55, the upper end of which is provided with a depending arm 56 which supports the back rest pad 57. Slide 55 carries an adjustable, auxiliary slide 58 for supporting the head rest.

The present head rest comprises, in addition to the slide 58, a swiveling head 59, Figs. 1, 3 and 4, supporting at its upper end the shank bar 60 of a yoke 61. The head 59 has a swiveling connection at opposite ends with the parts 58 and 60, respectively, and includes means operated by a handle 62, for clamping such parts in adjusted position.

Yoke 61 has threaded openings in its ends for the reception of threaded studs 63, Figs. 3 to 8, inclusive, locked in adjusted position by nuts 64. Studs 63, extending inwardly of the yoke have reduced portions 65 (Fig. 8) and terminate in enlarged heads 66 for the purpose hereafter described. Within the outer yoke 61 is an inner yoke 67 having openings in its ends for the reception of the inner ends of the studs 63 on which the inner yoke is pivoted. Each end of the inner yoke is formed with a bearing opening 68, Fig. 7, extending transversely of the studs 63, for the reception of opposed trunnions 69 carried by spaced arms 70 on head rest members 71. Trunnions 69 have portions rotatably fitted in opening 68 of the inner yoke, the outer ends of the trunnions being squared and fitting in square openings in arms 70 so that pivotal adjustment of the head rest members 71 is accomplished by turning the trunnions in their bearings 68 of the inner yoke. The trunnions are formed at their inner ends with eccentrics 72 positioned in the reduced portion 65 of stud 63, and adapted, on rotation, to bear against head 66 of the stud, for clamping the parts in position, as hereinafter described.

Each head rest member 71 comprises the usual cupped circular head pad 73 and also a substantially plane-shaped portion 74 having a substantially flat surface 75 for supporting the head of the patient in certain examinations hereafter referred to. It is evident from the above construction that the pads 73 of members 71 may be rotated to head supporting position, as shown in

Fig. 6, during which movement the eccentrics 72 tend to press studs 63 outwardly while reacting inwardly upon the ends of the inner yoke, thus relieving any binding pressure on the pivotal parts of the inner yoke, and of head rest members 11. The pad portion of the head rest member is thus released for movement freely to position to accommodate the head of the patient. On the other hand, as each head rest member is swung to position its flat surface 75 in supporting position, as shown in Fig. 5, its stud eccentrics 72 bear inwardly on the inner head 66 of the stud 63, while reacting against the bearing in the end of the inner yoke, thereby drawing the ends of the inner and outer yokes into clamping engagement with each other and at the same time clamping the trunnions 69 of the head rest member 11, so that the latter and the inner yoke 67 are automatically clamped in position. The inner yoke may be adjusted at a desired angle 20 to the outer yoke, before being clamped, and the flat head supporting surfaces 75 may be arranged to lie substantially in the plane of the back rest in the horizontal position of the latter, as shown in Fig. 2 in which these parts and the 25 leg and foot rests form a substantially flat, table-like support. In this position the flat surfaces 75 furnish immovable supports on which the face, or the side or back of the patient's head may be rested during examination so as to prevent sagging of the patient's neck, as desirable during administration of anaesthetics.

The invention supplies an improved and advantageous arrangement of back and arm rests relative to the seat frame which produces an anatomically correct compensating hinge movement of the back and head rests, thus properly accommodating the movements of the back and head rests to the movements of the patient's body and so contributing materially to the patient's comfort. Such movement of the back and head rests is conveniently controlled by a locking lever uniformly positioned in rear of the back rest, so that these parts may be easily tilted to lie substantially in the plane of the chair seat, with spring means for counterbalancing the weight of the patient and chair parts during such movement.

It will thus be seen that the invention accomplishes its objects and while it has been herein disclosed by reference to the details of a preferred embodiment, it is to be understood that such disclosure is intended in an illustrative, rather than a limiting sense, as it is contemplated that various modifications in the construction 50 and arrangement of the parts will readily occur

to those skilled in the art, within the spirit of the invention and the scope of the appended claims.

I claim:

1. A head rest for a chair, characterized by a support, a pair of cup-shaped elements for supporting a patient's head, a pair of substantially flat head supporting elements, and means for adjustably mounting both pairs of said elements concomitantly on said support for selective pivotal movement of either pair thereof to head supporting position.

2. A head rest according to claim 1, characterized by two members each carrying respectively one of said cup-shaped and flat head supporting elements; said members being pivotally mounted on said support.

3. A head rest according to claim 2, characterized by an outer supporting yoke, an inner supporting yoke mounted in said outer yoke for pivotal movement about one axis, said two members being mounted on said inner yoke for pivotal movement thereon about another axis, and means actuated by pivotal movement of said members to a predetermined position on said inner yoke for automatically clamping said members and said inner yoke against movement about said axes, respectively.

4. A head rest according to claim 3, characterized by trunnions on one of said yokes on which the other of said yokes is mounted for pivotal movement, and by a stud on each of said members rotatably mounted on said inner yoke and formed with an eccentric portion engaging one of said trunnions, respectively, said eccentric portions being arranged for thrusting engagement with said trunnions to shift the same longitudinally and clamp said inner yoke and said members against movement when located with said flat elements in head supporting position.

NORMAN E. LAUTERBACH.
